CIRCUIT BREAKER CONTROL SYSTEM

Glen L. Claybourn, Pittsburgh, Pa., assignor to
Westinghouse Electric Corporation, East Pittsburgh, Pa., a corporation of Pennsylvania

Application May 5, 1948, Serial No. 25,237

4 Claims. (Cl. 171—97)

1

My invention relates, generally, to control systems and it has reference, in particular, to a circuit breaker control system for controlling the operation of a pair of feeder breakers and a feeder tie breaker, or the like.

Generally stated, it is an object of my invention to provide a circuit breaker control system that is simple and inexpensive to manufacture, and is reliable and effective in operation.

More specifically, it is an object of my invention to provide an automatic control system for selectively operating a pair of feeder breakers and a tie breaker connecting the feeders, so as to insure the maximum continuity of service for the feeders.

It is also an object of my invention to provide, in an automatic circuit breaker control system, for selectively operating a pair of feeder breakers and a tie breaker which connects the feeders so as to permit closing the tie breaker only when one of the feeder breakers is open.

Another object of my invention is to provide, in a feeder and tie circuit breaker control system, for preventing closure of the tie breaker to connect the feeders in the event that the reclosing means of either of the feeder breakers fails to effect reclosure of its feed breaker.

Yet another object of my invention is to provide, in a feeder and tie circuit breaker control system, for making the tie breaker the master element in determining whether or not the feeder breakers may be operated either manually or automatically.

It is an important object of my invention to provide, in a circuit breaker control system, for using auxiliary control relays of the mechanically-latched electrically-reset type for controlling the operations of a pair of feeder breakers connecting feeders to separate sources of electrical energy, and also controlling the operation of a tie breaker connecting the feeders.

Another important object of my invention is to provide, in a circuit breaker control system, for delayed operation of a tie breaker disposed to connect two feeders, in order that it may be first determined whether a change in the operating position of either feeder breaker is only momentary or lasts for greater than a predetermined time.

Still another object of my invention is to provide, in an automatic feeder and tie circuit breaker control system, for tripping the tie breaker whenever both feeders are separately energized from their respective sources, and also when neither feeder is energized from its separate source.

Yet a further object of my invention is to provide, in a feeder and tie circuit breaker control system, for selectively operating the tie and feeder breakers so as to provide the maximum

2

continuity of service to both feeders without requiring synchronizing of the separate feeder sources.

Other objects will, in part, be obvious, and will, in part, be explained hereinafter.

In practicing my invention in one of its forms, each of two feeders is connected to a separate source by a feeder breaker which is disposed to be operated either manually or automatically. 10 The feeders are connected by a tie breaker, and voltage responsive control means are utilized so that the tie breaker can only be closed when the voltage of one or the other of the sources fails. The control circuits of the feeder and tie breakers are so interlocked that if one or the other of the feeder breakers opens in response to a fault condition and is locked out after a predetermined number of reclosing operations, the tie breaker is prevented from reclosing and connecting the source of the other feeder to the faulty feeder. The closing circuits of the feeder breakers can only be completed when the tie breaker is opened, thus preventing connection of the separate sources, which are not synchronized.

25 For a more complete understanding of the nature and scope of my invention, reference may be made to the following detailed description which may be read in connection with the accompanying drawings in which:

30 Figures 1A and 1B, when placed side by side, provide a diagrammatic view of an automatic circuit breaker control system embodying the invention in one of its forms.

Referring generally to the drawings, the reference numerals 10 and 12 may denote generally a pair of feeder breakers for connecting feeder conductors 14 and 15 to separate sources of alternating current power represented by the conductors 17 and 18, respectively. A tie breaker 20 may be provided for connecting feeder conductors 14 and 15, which may be connected to suitable load circuits (not shown). The breakers may be of any suitable type, being for example, of the well-known drawout type, wherein the breaker is normally positioned in a metal housing or cell, (not shown) and from which it may be withdrawn to isolate it from its power circuit for test purposes.

The control apparatus for the feeder breaker 10 is, for the purposes of convenience, represented as contained within an enclosure 21 designated by a dot and dash line. The control apparatus for the circuit breaker 12 is represented as contained within an enclosure 22. Since the control apparatus for the other feeder breaker 10 is substantially identical with that of the feeder breaker 12, it has not been illustrated in detail, inasmuch as it is believed that this would unduly complicate the drawings. The control apparatus for the tie breaker 20 is represented as contained

within an enclosure 23. Common control equipment for the feeder and tie breakers is shown below the enclosures.

Referring to Fig. 1A, it will be seen that the feeder breaker 10 may comprise an armature 24 having an operating winding 25 which may be connected to a source of electrical energy through a cutoff switch 26 by means of a closing relay 27 having an operating winding 28, and an auxiliary or cutoff relay 29 having an operating winding 30. The closing relay 27 may be connected to the source of electrical energy through the cutoff switch 26, either by a manual control switch 31, which may be of the drum type, or by an automatic recloser 32. Trip means comprising an armature 33 having an operating winding 34 for actuating the armature 33 to release the armature 24, may be provided for tripping the feeder breaker 10, either in response to the operation of a current responsive protective relay 35, in response to operation of the manual control switch 31, or in response to operation of a voltage relay 36 which may be responsive to the voltage of the conductors 17. An interlock switch 10A may be provided for completing a control circuit when the breaker is withdrawn from its cell or housing.

The automatic recloser 32 may be of any suitable and well-known type, such as are commonly employed to effect a predetermined number of reclosures of a circuit breaker which has been opened in response to a fault condition. In this instance it is illustrated as a motor-driven switch type comprising a switching element 37 driven by a synchronous motor 38. The switching element 37 comprises a plurality of cams 39, 40, 41 and 42 for actuating movable contact members 39a, 40a, 41a and 42a into and out of engagement with associated stationary contact members 39b, 40b, 41b and 42b, respectively. The recloser may be disposed to effect periodic reclosures of the feeder breaker 10 effecting, for example, an instantaneous reclosure, and two subsequent reclosures at predetermined intervals of time. A reclosing relay 43 having an operating winding 44 may be energized through the moving and stationary members 41a and 41b to effect energization of the closing relay 27 for closing the feeder breaker. An auxiliary reclosing relay 45 having an operating winding 46 may be utilized in conjunction with the reclosing relay 43 to provide an energizing circuit for the closing relay 27.

Referring to Fig. 1B, it will be seen that the tie breaker 20 may comprise an armature 47 having an operating winding 48. Trip means comprising an armature 49 having an operating winding 50, may be provided for tripping the tie breaker. Operation of the tie breaker may be effected by means of a closing relay 51 having an operating winding 52, and which is operative to provide an energizing circuit for the operating winding 46 of the tie breaker. A cutoff relay 53 having an operating winding 54 may be provided for deenergizing the closing relay 51 as soon as the tie breaker closes. A manual control switch 55 of the drum type may be provided for manually closing or tripping the tie breaker. Interlock switches 20A, 20B and 20C may be provided in connection with the tie breaker 20 to provide for completing different control circuits when the breaker is withdrawn from its cell for test purposes.

A manual control switch 57, which may be of the drum type, may be provided for simultaneously connecting the control equipment of the circuit breakers 10, 12 and 20 for either manual

or automatic operation. Automatic operation of the feeder breakers 10 and 12 may be provided by utilizing, in connection with each of the breakers as shown in Fig. 1A, the voltage responsive relay 36 in connection with an auxiliary relay 62 for tripping the feeder breaker 10 in response to failure of voltage at the source conductors 17 and closing it in response to restoration of voltage. The voltage responsive relay 36 may, for example, be of the induction type so as to provide a predetermined time delay for its moving contact member 36a to swing from the normal voltage contacts 36b to engage the under voltage contacts 36c.

15 The auxiliary relay 62 may be of the mechanically-latched, electrically-reset type comprising, for example, an armature 63 having an operating winding 64 which may be disposed to be energized through the under voltage contacts 36c of the relay 36. Latch means 65 may be provided for maintaining the armature 63 in the operated position, and a reset winding 66 may be provided for releasing the latch means to restore the armature to the reset position. By utilizing the auxiliary relay 62 to trip the feeder breaker 10 in response to a voltage failure or low voltage condition on the source conductors 17, and to provide an energizing circuit for the closing relay 51 of the tie breaker 20, transfer of the feeder conductors 14 30 from the source conductors 17 to the source conductors 18 may be effected. By utilizing auxiliary contact members of the feeder breakers 10 and 12 to provide energizing circuits for the trip means of the tie breaker 20, whenever both of the feeder breakers are either opened or closed, interconnection of the conductors 17 and 18 may be prevented under such conditions.

In order to provide a reliable source of control voltage for operating the control equipment of the tie breaker 20, control transformers 67 and 68 may be provided in connection with the source conductors 17 and 18, respectively. Control means, such as the transfer relay 69, having an operating winding 70 may be provided for connecting the cutoff switch 71 which supplied electrical energy to the control equipment for the tie breaker 20, to either the conductors 72 and 73 on the secondary side of the control transformer 67, or to conductors 75 and 76 on the secondary side 50 of the control transformer 68, depending on whether or not the conductors 17 are energized.

In order to make the tie breaker 20 the master element in the control system, and prevent either one of the feeder breakers 10 or 12 from being closed when the other is closed and the tie breaker is also closed, auxiliary contact members 20d and 20e of the tie breaker 20, which are normally closed when the tie breaker is open, may be connected in the closing circuits of the feeder breakers 10 and 12. Interlock switches 20A and 20B, which are closed when the circuit breaker 20 is withdrawn from its cell so as to be incapable of connecting the feeder conductors 14 and 15, may be utilized to shunt contact members 20d and 20e, respectively, so that the feeder breakers may be closed when the tie breaker is closed in the "test" position. The limit switch 10A of the feeder breaker 10 may be utilized to permit closing the tie breaker when the feeder breaker is withdrawn 70 from its cell and contact members 10g are not effective.

With a view to preventing operation of the tie breaker 20 to connect the feeder conductors 14 and 15, in the event that either one of the feeder breakers 10 or 12 is locked out after failure of its

recloser to reclose it, means such as the lockout relay 82 may be provided, having an operating winding 83. The operating winding 83 may be connected for energization through contact members 42a and 42b of the recloser 32, which may be disposed in engagement whenever the breaker is locked open. The relay 82 may be disposed to interrupt the closing circuit for the tie breaker 20 by opening contact members 82a which may be connected therein whenever the recloser stops in the lockout position.

With the system in the deenergized position, as shown, the cutoff switch 26 of the feeder breaker 10 may be closed to connect the control equipment to the conductors 17 through control transformer 67. The voltage responsive relay 36 thereupon operates, so that the moving contact member 36a disengages contact members 36c and engages contact members 36b, so as to provide for operating the auxiliary relay 62 to the reset position in which it is shown.

With voltage on the conductors 17, the transfer relay 69 will operate to connect the cutoff switch 71 of the tie breaker 20 to conductors 72 and 73. Since the feeder breaker 10 is in the open position, an energizing circuit will be provided for the cutoff relay 29, extending from the cutoff switch 26 through conductor 85, contact member 31b, conductor 86, contact member 10b, resistor 88, operating winding 39 and conductor 89, back to the other side of the cutoff switch. The cutoff relay thereupon operates to the energized position. The feeder breaker 10 may now be closed by operating the manual control switch 31 to the "close" position, whereupon the "slip" contact member 31e closes.

Upon return of the switch to the "off" position, contact member 31e remains in the closed position, and an energizing circuit is provided for the reclosing relay 43, extending from one side of the cutoff switch 26 through conductor 89, conductor 90, resistor 91, contact member 10f, operating winding 44, contact member 45a, conductor 92, moving contact member 41a, stationary contact member 41b, conductor 93, conductor 94, "slip" contact member 31e, contact member 31d, conductor 95, contact member 62c, conductor 96, contact member 57b, conductor 97, contact member 20e, conductor 98 and conductors 102 and 85, back to the other side of the cutoff switch. At the same time, an energizing circuit is provided for the recloser motor 38, extending from conductor 94, through contact member 10d, conductor 121 and contact members 39a and 39b, through motor 38 and back to conductor 89 through conductor 88.

The reclosing relay 43 operates and provides an energizing circuit for the auxiliary reclosing relay 45 through contact member 43. A circuit is now completed for the closing relay 27, extending from conductor 89, through contact member 29b, operating winding 28, conductor 99, contact member 45b, contact member 43a, conductor 100, conductor 92, contact member 41a, contact member 41b, conductor 93, conductor 94, "slip" contact member 31e, contact member 31d, conductor 95, contact member 62c, conductor 96, contact member 57b, conductor 97, contact member 20e, conductor 98 and conductor 85, back to the other side of the cutoff switch.

The closing relay 27 operates to the energized position and provides an energizing circuit for the operating winding 25 of the feeder breaker 10, extending from the conductor 85 through conductor 102, conductor 103, contact member 27b, 75

operating winding 25, conductor 105, and conductor 89, back to the other side of the cutout switch.

When the feeder breaker 10 closes, the cutoff relay 29 is shunted down through contact member 10c of the breaker, thus providing for interrupting the energizing circuit of the operating winding 28 of the closing relay 27. The recloser 32 operates to interrupt the energizing circuits for the reclosing and auxiliary reclosing relays 43 and 45, and finally stops in the reset position, as shown. The operation of the control equipment for the feeder breaker 12 will be similar, so that normally the feeder breakers 10 and 12 connect the feeders 14 and 15 to the separate source conductors 17 and 18, respectively.

Should voltage fail on the conductors 17, the voltage responsive relay 36 responds by slowly moving the contact member 36a in a clockwise direction. After a predetermined time interval, contact member 36a engages contact member 36c and an obvious energizing circuit is provided for the operating winding 64 of the auxiliary relay 62. The auxiliary relay 62 operates, and provides a trip circuit for the trip winding 34, of the feeder breaker 10, extending from negative through contact member 10a, trip winding 34, conductor 107, contact member 62b, conductor 108, and contact member 57a to positive. The feeder breaker 10 is thereby released to the open position. Since the reclosing circuit originally traced passed through contact member 62c of the auxiliary relay which is now in the open position, the recloser 32 cannot operate to reclose the feeder breaker.

When the auxiliary relay 62 operates, an energizing circuit is thereupon provided for energizing the closing relay 51 of the tie breaker 20. This circuit extends from the upper terminal of the cutout switch 71, through conductor 110, contact member 53b of the cutoff relay, operating winding 52, conductor 111, conductor 112, contact member 82a, contact member 10g, conductor 113, contact member 62d, conductor 114, contact member 57c and conductor 115, to the lower terminal of the cutout switch 71.

The cutout switch 71 is now energized from the control transformer 68, since upon failure of voltage at the source conductors 17, the transfer relay 69 returns to the deenergized position as shown. When the closing relay 51 operates, it provides an energizing circuit for the operating winding 48 of the tie breaker 20 through contact member 51b. The tie breaker closes, and connects the feeder 14 to the source conductors 18. Upon closure of the tie breaker 20, the cutoff relay 53 is shunted down by contact member 20c, and interrupts the energizing circuit for the closing relay 51.

Upon the return of voltage to the source conductors 17, the transfer relay 69 operates to the energized position, and transfers the connection of the cut out switch 71 back to the source conductors 17. After a predetermined interval of time the moving contact 36a of the voltage responsive relay 36 engages stationary contact members 36b, so that an obvious energizing circuit is provided for the reset winding 66. The auxiliary relay 62 thereupon returns to the reset position as shown. This provides an energizing circuit for the trip winding 50 of the tie breaker 20, extending from negative through contact member 20a, trip winding 50, conductor 117, a closed contact member of the auxiliary relay of feeder breaker 12, which corresponds to the auxiliary relay 62 of breaker 10, conductor 119,

contact member 62c, conductor 120, contact member 57d, to positive. The tie breaker 20 opens, and a closing circuit is provided for the feeder breaker 10 as described hereinbefore. The feeder breaker 10 thereupon closes, and reconnects the feeder conductors 14 to the source conductors 17.

Should a fault occur on either of the feeders, for example the feeder conductors 14, the current responsive relay 35 operates and provides an obvious energizing circuit for the trip winding 34 of feeder breaker 10 through contact member 35a. As soon as the feeder breaker 10 opens, an energizing circuit is provided for the reclosing relay 43 through the circuit hereinbefore traced through contact member 10f of the feeder breaker. At the same time, an energizing circuit is provided for the motor 38 of the recloser, extending from the cutout switch 26 through conductor 89, conductor 90, conductor 87, motor 38, contact member 39b, contact member 39a, conductor 121, contact member 10d and conductor 94, back to the conductor 85 through the circuit previously traced for the reclosing relay 43.

Operation of the reclosing relay 43 in conjunction with the auxiliary reclosing relay 45 provides an energizing circuit for the closing relay 27, which effects energization of the operating winding 25 of the feeder breaker 10. Upon closure of the feeder breaker, the cutoff relay 29 is shunted down and interrupts the energizing circuit for the closing relay. Should the feeder breaker 10 remain in the closed position, the recloser motor 38 continues to run until it is restored to the position shown upon the opening of contact member 40a, whereupon it is reset for a subsequent reclosing operation.

Should the feeder breaker 10 fail to remain closed after the first reclosure, a second reclosure takes place upon actuation of the contact member 41a by the next projection on the cam 41. Should the breaker still fail to stay closed, a third reclosure will be effected, whereupon the operating circuit for the reclosure motor 38 will be interrupted with the contact member 42 in engagement with the stationary member 42b. This provides an obvious operating circuit for the lockout relay 82, which thereupon operates to the energized position, thus interrupting the closing circuit for the tie breaker 20. The tie breaker is thereby prevented from connecting the faulty feeder conductors 14 to the source conductors 18. Upon removal of the fault on the conductors 14, the feeder breaker 10 may be reclosed manually by operating the manual control switch 31 and the control switch 57. The recloser 32 thereupon operates to the reset position as shown, and is ready for a subsequent reclosing operation.

Should the tie breaker 20 be closed, it will be impossible to close either one of the feeder breakers 10 or 12 should the other one be closed, since both the manual and automatic reclosing circuits for these feeder breakers must pass through contact members 20c and 20d, respectively, which are only closed when the tie breaker is opened. Thus, neither manual or automatic operation of the feeder breakers to the closed position may be effected when the tie breaker is closed. Should the tie breaker 20 be removed from its cell, contact members 20d and 20e will be shunted by the cell interlock contact members 20A and 20B, thus permitting closing of the feeder breakers when the tie breaker is closed, but is in the "test"

position, in which it is removed from its cell and is, therefore, ineffective to connect the conductors 14 and 15.

From the above description and the accompanying drawings it will be apparent that I have provided in a simple and effective manner for insuring the maximum continuity of service to feeder circuits which are normally energized from non-synchronized alternating current power sources. The tie breaker is utilized as a master control device for determining whether the feeder breakers may be manually or automatically closed. The feeder breakers are automatically opened and the tie breaker is closed upon loss of or reduction in voltage to the respective feeders from their separate sources. The continuity of service to either feeder is protected in the event of a fault occurring on the other feeder, since the tie breaker is prevented from closing in the event that either feeder breaker is locked out.

Since certain changes may be made in the above-described construction and different embodiments of the invention may be made without departing from the spirit and scope thereof, it is intended that all the matter contained in the above description and shown in the accompanying drawings, shall be considered as illustrative and not in a limiting sense.

I claim as my invention:

1. A transfer control system for a pair of feeders disposed to supply electrical energy to load circuits and a tie breaker operable to connect the load circuits comprising, a feeder breaker disposed to connect each feeder to a separate source of alternating current, reclosing means associated with each feeder breaker to reclose said breaker a predetermined number of times after it opens in response to a fault on its feeder and operable to lock said breaker in the open position upon failure to stay reclosed within the predetermined number of reclosures, control means operable in response to closing of the tie breaker to render the reclosing means inoperative, and relay means operable in response to failure of one of said feeder breakers to stay reclosed within the predetermined number of reclosures to prevent operation of the tie breaker.

2. A circuit breaker system for controlling the supply of electrical energy to a pair of feeders comprising, a circuit breaker disposed to connect each feeder to a separate source of electrical energy, control means associated with each feeder breaker operable to trip said breaker upon failure of voltage of the associated source, a normally open tie breaker disposed to connect the feeders together, circuit means controlled by said control means connected to normally provide a closing circuit for the tie breaker, and fault means responsive to tripping of a feeder breaker in response to a fault condition operable to render the circuit means ineffective to complete said closing circuit.

3. A circuit breaker system comprising, a pair of feeder circuit breakers each disposed to normally connect a feeder to a source of alternating current, current responsive means operable to trip the breakers in response to current in excess of a predetermined value, reclosing means connected to normally provide a reclosing circuit for reclosing each feeder breaker a predetermined number of times, a tie breaker disposed to connect the feeders together, control means responsive to the voltage of one of the sources to provide for selectively tripping the associated

feeder breaker or rendering its reclosing means operable, said control means being also effective to selectively provide a closing circuit or a trip circuit for the tie breaker, and lockout means responsive to failure of the feeder breaker to remain closed after the predetermined number of reclosures by the reclosing means, said lockout means being effective to prevent completion of the closing circuit of the tie breaker.

4. In a control system, a pair of feeder circuit breakers disposed normally to connect feeder conductors to separate sources of alternating current, a closing relay for each of the feeder breakers, automatic reclosing means operable to provide an operating circuit for the closing relay and effect a predetermined number of reclosures of one of the feeder breakers in response to tripping of the breaker in response to a feeder fault, manual control means operable to provide an operating circuit for the closing relay, transfer means operable to render only one of the automatic reclosing or manual control means effective, a tie breaker disposed to connect the feeders to-

gether, circuit means responsive to closing of the tie breaker to render both the automatic reclosing and manual control means ineffective, relay means responsive to the voltage of one of the sources operable to provide for selectively tripping or closing its associated feeder breaker in response to loss of voltage at said one source or restoration thereof and selectively closing or tripping the tie breaker, and lockout means responsive to failure of a feeder breaker to reclose in the predetermined number of reclosures operable to render said relay means ineffective to close the tie breaker.

GLEN L. CLAYBOURN.
